SEPARABLE MOUNTING FOR
MEMORANDA PADS

Lew W. Hamilton, Chicago, Ill.

Application March 25, 1948, Serial No. 16,996

4 Claims. (Cl. 281—19)

1

This invention relates to a separable mounting for memoranda pads and the like.

Certain known mountings for memoranda pads of this general character are objectionable in that they do not adequately secure the pads to the holder members or, in their constructions, require a plurality of parts, which increases the cost of fabrication of the same. Accordingly, it is an object of my invention to provide a separable mounting for memoranda pads or the like which is highly efficient in operation and which is simple and inexpensive to manufacture. With these ends in view, I have devised a novel separable mounting for memoranda pads and the like of which the following description, in connection with the accompanying drawings, is a specification, reference characters being used to designate the several parts.

Other aims, objects and purposes of my invention will become apparent as the disclosure proceeds.

In the drawings:

Fig. 1 is a plan view of a memoranda pad and mounting illustrating the application of the invention.

Fig. 2 is a similar fragmentary view on an enlarged scale with the sheets of the pad removed and showing the elements in assembled relation.

Fig. 3 is a fragmentary front perspective view of the supporting member of my separable mounting.

Fig. 4 is a fragmentary rear perspective view of a memoranda pad showing a cooperating element of the mounting attached thereto.

Referring now to the drawings, wherein is shown a preferred embodiment of my invention, the numeral 5 designates a supporting member which is formed of suitable material such as cardboard, fiber board, or plastic. It is contemplated that the member 5 will carry on its surface suitable advertising indicia or printed matter. The member 5 is die-cut, as shown more clearly in Fig. 3, to provide two spaced parallel slits 6 and 7 and a cut-out portion 8, preferably rectangular in shape, connected with each slit at the top portion thereof. The cut-out portions 8, 8 are arranged with their lower edges 9 and 11 in alignment and at right angles to the slits 6 and 7 and, in effect, form, with the longitudinal slits 6 and 7, inverted L-shaped slits, the said lower edges serving as shoulders to support the cooperating element of the mounting, hereinafter to be described. As will be apparent, the portion 13 of the member 5 located between the slits 6 and 7 is sufficiently flexible as to be

2

capable of being bowed or displaced rearwardly, out of the plane of the member 5.

The cooperating element 12 of the mounting is shown more clearly in Fig. 4 and comprises a backing or supporting member 14 formed of suitable cardboard material and is, preferably, coextensive in area with the memoranda pad 16 comprising a plurality of sheets of paper. The member 14 may be attached to the pad 16 in any well known manner, as by staples or glue, the glue being applied along the top edge thereof. The member 14 is die-cut, as shown, along lines 17, 18 and 19, with the lines 17 and 19 converging towards each other to provide a tapered tongue 21, which is displaceable out of the plane of the member 14, the tongue being of greater width than the portion 13 between the slits 6 and 7. It will be observed that the die-cut lines 17 and 19 begin at points 23 and 24 respectively, which are spaced from the top and side marginal edges of the member 14, and that the tongue 21 is hinged along a line connecting these two points.

While the member 14 has been described as being preferably coextensive in area with the memoranda pad 16, it will be understood that the member 14 may be smaller in area than the pad 16, or may comprise only the tongue portion 21, having shoulders extending from the points 23 and 24 to the marginal side edges and substantially parallel to the top edge of the pad 16. A backing member 14 coextensive in area with the pad 16, however, is preferred, since it facilitates production of the pad in that the said member is cut to size simultaneously with the pad of paper, and also because uniform thickness throughout the area of the pad is obtained, thereby permitting even stacking of the pads in storage.

To mount the pad 16 on the member 5, the tongue 21 is pushed out of the plane of the member 14 and the end of the tongue 21 inserted in the cut-out portions 8, 8, the portion 13 of the member 5 being thereby displaced rearwardly out of the plane of the member to permit the tongue 21 to enter between the portion 13 and the portions 26 and 27 of the member 5 adjacent thereto. The tongue 21 is thus confined on its rearward side by the portion 13 and on its forward side by the portions 26 and 27. These portions together cooperate to frictionally retain the tongue 21 substantially in flat condition contiguous to the plane of the member 5. When the elements of the mounting are properly assembled, the points 23 and 24 of the member 5 abut the lower edges 9 and 11 of the cut-out portions 6

and 7 respectively, which edges act as shoulders, thereby limiting the depth of insertion of the tongue 21 into the receiving pocket thus formed.

When all of the sheets of the memoranda pad 16 have been exhausted, the member 14 is moved upwardly to disengage the tongue 21 from its receiving pocket, and a new pad is thereafter inserted therein. Thus, a considerable economy in production and use is effected, since a supporting member such as 5, which may usually bear advertising indicia, may be reused indefinitely, it being only necessary to replace the memoranda pads 16 when the same have been exhausted.

While the invention has been described with relation to its application to memoranda pads, it will be understood that the sheets of the pads may carry printed matter, and the pads, for example, may be in the form of calendar pads which may be replaced when required.

I claim:

1. A separable mounting for memoranda pads comprising a supporting member slit along two spaced lines to provide a strip connected at both ends thereof, but displaceable for the greater part of its length out of the plane of said member and a cut-out portion on each side of said strip immediately adjacent thereto, and a member attachable to a pad and having a tongue of greater width than said strip, said tongue being insertable in said cut-out portions and receivable longitudinally in the slits forwardly of said strip.

2. In combination a supporting member slit along two spaced lines to provide a strip connected at both ends thereof, but displaceable for the greater part of its length out of the plane of said member and a cut-out portion on each side of said strip extending transversely thereof, and a member attachable to a pad and having a tongue of greater width than said strip, said tongue being insertable in said cut-out portions and receivable longitudinally in said slitted lines forwardly of said strip.

3. A separable mounting for memoranda pads and the like comprising a supporting member slit along two spaced lines to provide a strip connected at both ends thereof but displaceable

for the greater part of its length out of the plane of said member, said member having a cut-out portion on each side of said strip immediately adjacent thereto with the lower edge of each cut-out portion forming a supporting shoulder, and a backing member attachable to a pad and having formed therein a tongue hinged at one end, said tongue when displaced out of the plane of said backing member forming a shoulder along the juncture thereof with said backing member, said tongue being so constructed and arranged as to be receivable in said cut-out portions and said slits forwardly of said strip with said shoulders cooperating to support said pad and said backing member on said supporting member.

4. In combination a supporting member slit along two spaced vertical lines to provide a strip connected at both ends thereof but displaceable for the greater part of its length out of the plane of said member, said member having a cut-out portion on each side of said strip immediately adjacent thereto and extending transversely thereof with the lower edge of each cut-out portion forming a supporting shoulder, and a backing member attachable to a pad and having formed therein a tongue hinged at one end, said tongue when displaced out of the plane of said backing member forming a shoulder along the juncture thereof with said backing member, said tongue being so constructed and arranged as to be receivable in said cut-out portions and said slits forwardly of said strip with said shoulders cooperating to support said pad and said backing member on said supporting member.
